RING RAIL LATCH FOR SPINNING FRAMES AND THE LIKE

Bobo B. Rogers, 2407 Wallace Ave., Spartanburg, S.C.

Filed Nov. 8, 1961, Ser. No. 151,052

5 Claims. (57-54)

The present invention relates to spinning frames and the like, and more particularly to an improved latch mechanism for retaining the ring rail in the depressed position.

Conventionally, the ring rail on a spinning frame is traversed relative to the spindles by a builder mechanism upwardly from a starting position to a finishing position. To doff the full bobbins from the spindles, the ring rail must be moved to a depressed or doffing position closely adjacent to the bottom of the filled bobbins. The conventional mechanism for moving the ring rail to the depressed or doffing position comprises a foot treadle upon which the operator places his foot and exerts downward pressure thereon to manually move the ring rail to the doffing position.

Due to the large force which is required to move the ring rail to the doffing position, it is difficult for the operator to manually engage conventional latches. Also, difficulty has been encountered in stopping the ring rail at the correct position for engagement of the latches and this is particularly true with the slot type of latch. In this regard, an inherent deficiency in all of these prior latches is that no effective means is provided for limiting the downward movement of the foot treadle toward the doffing position which sometimes results in the ring rail being moved too far. When this occurs, the ring rail is moved into contact with the tapes which drive the spindles resulting in damage to the tapes due to friction and possible breakage thereof. This materially reduces the life of such tapes and thereby materially increases the maintenance cost of the machine. Also, the ring travelers are moved to a position below the bottom of the bobbins which results in the yarn being wound around the spindle. It is therefore necessary for this yarn to be removed from the spindles before the same can be again placed into production.

It is therefore an object of the present invention to provide an improved latch mechanism for maintaining the ring rail in the doffing position which is automatically moved into operative latching position when the ring rail is moved to this position.

A more specific object of the present invention is to provide an improved latching mechanism of the character last described wherein the latch mechanism is biased toward the latched position and includes a cam surface thereon which is positioned in the path of travel of the foot treadle toward the doffing position such that the latch mechanism is moved from its normal position as the foot treadle moves thereby and is snapped into latching position thereover when the treadle moves out of contact with the cam surface.

A more specific object of the present invention is to provide a latching mechanism of the character described wherein the downward movement of the ring rail is limited such that the same does not move below the bottom end of the bobbin.

Some of the objects of the invention having been stated, other objects will appear as the description proceeds, when taken in connection with the accompanying drawings, in which—

FIGURE 1 is a side elevational view of a spinning frame incorporating the features of the present invention with portions broken away;

FIGURE 2 is an enlarged elevational view of the latch mechanism and adjacent parts of the builder mechanism

2

shown in the lower right-hand portion of FIGURE 1; and

FIGURE 3 is a vertical section taken substantially along line 3—3 in FIGURE 2.

5 Referring now to the drawings, there is shown a spinning frame 10 which includes a frame 11, a plurality of rotating spindles 12 driven in conventional manner by tapes 13. Tapes 13 are driven by the conventional cylinder (not shown) which is rotated by a pulley 14. Pulley 14 is driven by a plurality of belts 15 which in turn are driven by a drive pulley 16 of a motor 17.

10 Spindles 12 support suitable bobbins 18 on which is wound the yarn supplied by suitable roving bobbins 19 supported by a creel 20 mounted on frame 11. The 15 roving from bobbins 18 passes through a suitable drafting mechanism 21 downwardly through suitable thread guides (not shown) and through a traveler (not shown) mounted on suitable rings which in turn are mounted on a ring rail 22.

20 Ring rail 22 is mounted for traversing movement longitudinally of spindles 12 by a pair of lifter rods 23 slidably mounted in suitable bearings 24 mounted on frame 11. A lifter arm 25 is pivotally connected at one end to the lower end of each of the lifter rods 23 and at the 25 other end to brackets 26 mounted on frame 11 by a pivot pin 27. Lifter arms 25 are moved about the pivots 27 by a suitable builder mechanism (not shown) in a manner which is conventional in this art and forms no part of this invention.

30 A foot treadle member 28 is fixedly mounted on one of the lifter arms 25 and is adapted to receive thereon the foot of an operator of the spinning frame to move the ring rail 22 downwardly against the counter balance weights (not shown) to a depressed position for doffing of the bobbins 18 from the spindles 12. It is extremely desirable in moving the ring rail to the doffing position that the same not move downwardly beyond the lower end of the bobbins 18 to prevent the yarn from being wound on the spindles 12 and to prevent the ring rail 22 from coming into contact with the tapes 13.

35 A latching mechanism 30 comprises a first member 31 which includes a generally horizontally extending portion 32. Member 31 is mounted on frame 11 by a bolt member 33 which penetrates through aligned openings in the frame 11 and the portion 32 of member 31 and threadably receives a nut 34 on the opposite end. A second member 35 is mounted on member 32 for vertical adjustment relative to frame 11 and hence ring rail 22 by a pair of bolt members 36 which penetrate through a 40 vertical elongate slot 37 and through suitable openings formed in member 35 and aligned with said slot. Bolt members 36 have a pair of nuts 38 threadably mounted on the opposite end thereof for locking member 35 in 45 adjusted position. Member 35 has a generally horizontally extending portion 40 extending outwardly therefrom in a direction and of such length so as to underlie treadle member 28.

50 Member 35 has an elongate opening 41 formed therein, the lower end of which is spaced slightly above portion 40. A latch member 42 is pivotally mounted on member 35 within slot 41 by a bolt 43 which extends through aligned openings formed in member 35 and latch member 42 threadably receives a nut member 44 on the opposite end thereof. It is noted that the opening in latch member 45 is of slightly greater diameter than bolt 43 to allow 55 free pivotal movement of latch member 42.

55 Latch member 42 has a cam surface 45 defining the front edge, said cam surface curving downwardly and outwardly from the pivot point formed by bolt 43, such that at least the lower front corner portion of latch member 42 is normally positioned in the path of travel of treadle member 28. Latch member 42 is movable about

its pivot 43 from this normal position to a position out of the path of travel of the treadle member 28 by the engagement of cam surface 45.

A leaf spring member 50 is mounted on member 35 by a pair of bolts 51 threadably received in suitable internally threaded openings formed in member 35. Spring member 50 extends downwardly from bolts 51 to a position substantially even with the lower edge of latch member 42 and engages the lowermost rear corner. Spring member 50 thereby biases latch member 42 to the aforementioned normal position in the path of travel of foot treadle member 30, but allows the same to move about its pivot 43 out of the path of travel as the treadle member moves downwardly and engages the cam surface 45.

In operation, when it is desired to doff the bobbins 18 from the spindles 12, the ring rail 22 is normally positioned at the highest elevation in its traversing movement of the spindles 12. To move the ring rail to the doffing position so that the bobbins 18 may readily be removed from spindles 12, the operator places his foot on the treadle member 28 and applies downward pressure thereto. This downward pressure overcomes the action of the counterweights (not shown) and moves the ring rail 22 downwardly.

As the treadle member 28 moves downwardly, the same engages the cam surface 45 on latch member 42 and cams the latch member rearwardly or to the left, as shown in FIGURE 3, about its pivot 43 and against the action of spring 50. As treadle member 28 continues its downward movement, the same moves past the lower front corner, or right-hand corner in FIGURE 3, of latch member 42 and engages the horizontally extending stop portion 40 which limits the downward movement thereof. The latch member 42 is moved back to the normal position in the path of travel of treadle member 28 by spring member 50 as the treadle member moves downwardly past the lower front corner. The construction and shape of the latch member 42 is such that when the operator releases the downward pressure on treadle member 28, the counterweights will raise the treadle member upwardly until the same engages the bottom surface of latch member 42 which will restrict further upward movement and will releasably hold the treadle member, and hence the ring rail 22, in the doffing position.

It is noted that the horizontally extending stop portion 40 is vertically adjustable relative to the ring rail 22 by the elongate slot 37 and bolt members 36 such that the lowermost limit of the downward travel of ring rail 22 may be accurately positioned such that the ring rail may not move downwardly past the lowermost end of bobbins 18.

To release the latch 42 and allow the ring rail 22 to move upwardly in its traversing movement, the operator places his foot against the treadle member 28 and applies pressure to latch member 42 to move the same rearwardly about pivot 43 against the action of spring 50 until the lower front corner moves out of overlying relation to treadle member 28 and allows the same to move upwardly through the action of the counterweights. When the operator releases the pressure on latch member 42, spring 50 returns the same to the normal position in the path of travel of treadle member 28.

It will therefore be apparent that an improved latching mechanism for the ring rail of a spinning frame is provided which limits the downward movement of the ring rail and is automatically engaged when the ring rail arrives at the doffing position.

In the drawings and specification there has been set forth a preferred embodiment of the invention and, although specific terms are employed, they are used in a generic and descriptive sense only and not for purposes of limitation, the scope of the invention being defined in the claims.

I claim:

1. In a spinning frame having a plurality of rotating spindles, a ring rail mounted for traversing movement longitudinally of said spindles, a builder mechanism for moving said ring rail in said traversing movement, and a treadle member connected to said ring rail and movable therewith, said treadle member being adapted to be manually lowered to move said ring rail to a bobbin doffing position; the combination of

(a) a latch member mounted for movement between a first position wherein at least a portion thereof is disposed in the path of travel of said treadle to the lowered position and being adapted to overlie said treadle when the same is in the lowered position, and a second position spaced from said first position and out of the path of travel of said treadle, said latch member having a cam surface on said portion which is adapted to be engaged by said treadle as the treadle moves to the lowered position for moving said latch member from said first position to said second position to allow said treadle to move thereby, and

(b) spring means biasing said latch member toward said first position to normally maintain the latch member in the path of travel of said treadle.

2. The structure recited in claim 1 wherein said spring means comprises a leaf spring mounted adjacent to and operatively engaging the side of said latch member opposite from said cam surface.

3. In a spinning frame having a plurality of rotating spindles, a ring rail mounted for traversing movement longitudinally of said spindles, a builder mechanism for moving said ring rail in said traversing movement, and a treadle member connected to said ring rail and movable therewith, said treadle member being adapted to be manually lowered to move said ring rail to a bobbin doffing position; the combination of

(a) means mounted on said spinning frame and depending downwardly therefrom,

(b) stop means carried by said means and serving to define an abutment for limiting the downward extent of movement of said treadle member, and

(c) a spring biased latch member carried by said means and being positioned above said stop means and serving to define therebetween a gap for reception of said treadle member when moved to lowered position.

4. In a spinning frame according to claim 3 wherein said means depending from said spinning frame comprises a vertically adjustable member, and said latch member and stop means are carried by said member whereby the gap defined therebetween may be vertically adjusted by movement of said member to thus vary the extent of movement of the treadle member to the lowered position.

5. In a spinning frame having a plurality of rotating spindles, a ring rail mounted for traversing movement longitudinally of said spindles and movable to a bobbin doffing position, a builder mechanism for moving said ring rail in said traversing movement and a treadle member connected to said ring rail for manual movement of said ring rail to the bobbin doffing position; the combination of

(a) stop means positioned in the path of travel of said treadle member and serving to limit the downward movement thereof,

(b) a latch member having at least a portion thereof positioned in the path of travel of said treadle member, said portion of said latch member being positioned above said stop means and serving to define therebetween a gap for reception of said treadle member when in lowered position, said latch member having a cam surface on said portion engageable by said treadle member to move said latch member about its pivot to move the same out of the path of

said treadle member to allow the same to move therepast, and

(c) spring means operatively connected to said latch member for biasing said latch member into the path of travel of said treadle member whereby said latch member portion is positioned in overlying latching relation to said treadle member when the treadle

member has moved downwardly into engagement with said stop means.
